PACKING ELEMENT

Elbert B. Kincaid, Cincinnati, Ohio, assignor to
 Container Corporation of America, Chicago,
 Ill., a corporation of Delaware

Application August 24, 1950, Serial No. 181,283

4 Claims. (Cl. 206—62)

1

The present invention relates to a packing element of paperboard or like material, and more particularly to a packing element especially well adapted to protect fragile articles of relatively thin, flat conformation, such as glass sheets, mirrors, framed pictures, and the like, from breakage or other damage in shipment.

Stated briefly, the invention is embodied in a strip of paperboard divided into a plurality of pairs of panels, the panels of each pair being spaced apart longitudinally of the strip. A pair of laterally spaced straps connects the panels of each pair, and a pair of flaps each connected to one of the panels lies between the straps. A tongue substantially aligned with the flaps is cut from one of the panels, with its base adjacent the panel edge connected to the straps and its free end remote therefrom in its initially formed condition. At its free end, the tongue has a pair of lateral projections. The straps are bent to extend out of the planes of the panels, which are disposed closer to each other than the length of the unbent straps, the flaps overlapping each other. The tongue is folded about its base to extend between the straps and over the flaps, with its free end overlying the other panel and the lateral projections engaging the straps at the connections between that panel and the straps. The tongue engages the strap edges in frictionally locking relation, and this with the engagement of the projections on the straps holds the panels and straps in secured relation. A base member may be provided underlying and secured to the panels and bridging the space therebetween. Sheet-like articles, as for example sheets of glass, may be disposed with marginal portions between the straps and their edges engaging the tongue surface. The flaps and tongue space and cushion the sheet edges from the wall of a shipping case against which the panels lie, and the straps space and cushion the outer faces of the sheets from other walls of the case. Thus shocks in handling or shipment are absorbed or minimized by the packing element, and the sheets are held out of contact with the case even upon deflection of the case walls by blows or pressure. The several pairs of panels with their connecting straps are hinged for angular disposition relative to each other, so that the packing element may extend about a corner of the sheets, or may be disposed on or along an edge thereof. The packing element may be formed of sufficient length to extend completely about the sheet edges, or more than one element may be used to accomplish the encirclement, and will conform

2

closely to the peripheral contour of the sheets, whether such contour is straight or curved. The packing element is easily set up from a simple blank.

5 It is one object of the invention to provide a packing element for spacing packed articles such as glass sheets from the walls of a packing or shipping case. Another object is the provision of a packing element for flat articles such as glass sheets which cushions the edges and also the faces of the articles from the walls of the shipping case. A further object is the provision of a packing element for flat articles which is adapted to serve either about a corner or along an edge 10 thereof. Still another object is the provision of a packing element which may be applied about the entire periphery of packed articles such as flat sheets. It is also an object of the invention to provide a packing element of paperboard or 15 the like adapted to engage about the edges of articles such as flat sheets in close contour-following relation. An additional object is the provision of a packing element of paperboard or the like particularly adapted for use on flat sheets 20 which is readily formed from a simple blank and maintains itself in set-up condition. Still another object is the provision of a blank of paperboard or the like for such a packing element which is simple to form and to set up.

25 30 Other and further objects, advantages, and features of the invention will be apparent to those skilled in the art from the following description, taken with the accompanying drawings, in which:

Fig. 1 is a perspective view of one form of the 35 packing element of this invention arranged as a corner packing;

Fig. 2 is a perspective view of the packing element of Fig. 1 arranged as an edge packing, with a portion broken away for greater clearness;

40 Fig. 3 is a plan of a blank for the packing element of Figs. 1 and 2;

Fig. 4 is a perspective view of another form of the packing element of the invention, with a portion broken away;

45 Fig. 5 is a side elevational view of the element of Fig. 4;

Fig. 6 is a plan of a blank for the packing element of Fig. 4;

50 Fig. 7 is a sectional view taken along line 7—7 of Fig. 5, but showing the element as applied to a plurality of sheets and disposed in a case;

Fig. 8 is a fragmentary perspective view of still another form of the packing element;

55 Fig. 9 is a fragmentary enlarged side elevation

of the packing element of Fig. 8, as applied about the edge of a sheet; and

Fig. 10 is a shortened plan view of a blank for the packing element of Fig. 8, the mid portion being broken away.

Referring first to Figs. 1 to 3 of the drawings, there is shown a blank 10 from which the packing element 11 comprising one embodiment of the invention is formed. The blank 10 comprises a plurality of serially connected panels each of which extends entirely across the blank, and is formed in this instance of double face corrugated paperboard. In the present case, the blank 10 is divided into two symmetrical parts or sections by a central transverse hinge line 12, on each side of which is a panel 13. To each of the panels 13 is connected a panel 14, and connected to each of the panels 14 is a terminal panel 15. Each panel 14 is cut by a pair of parallel slits 16 extending longitudinally of the blank from end to end of the panel and a transverse slit 17 extending from one slit 16 to the other. A strap 18 connecting the panels 13 and 15 is defined between each slit 16 and the adjacent edge of the blank, and a pair of flaps 19 each extending from and integral with one of the panels 13 and 15 is formed between the slits 16 by the slit 17. A transverse fold line 20 is provided at the center of each strap 18, and a fold line 21 is provided at each end of each of the straps. The fold lines 21 define the connections between the straps and the panels 13 and 15, and may be parts or extensions of fold lines 22 which may be provided to define the ends of the panels 14 or the connections between the flaps 19 and the respective panels 13 and 15.

From each of the terminal panels 15 is formed a tongue 23 which is connected at its base to the remainder of the panel by a hinge line 24, in this case extending entirely across the panel. The tongue is of substantially the same width as the flaps 19 and aligned therewith, the hinge line 24 being spaced somewhat from the adjacent fold line 22 and the free end of the tongue lying at the end of the panel 15 remote from the straps. At its free end, which is at the end of the blank, the tongue is formed with lateral projections 25, and may have similar projections 26 at its base.

The packing element 11 is formed from the blank 10 by folding the straps 18 out of the plane of the blank about the fold lines 20 and 21, disposing the panels 13 and 15 closer to each other than the length of the unbent straps but still spaced apart, and with the flaps 19 overlapping each other. Each tongue 23 is bent on its hinge line 24 to extend between the bent straps, overlying the flaps 19 with its longitudinal edges frictionally engaged with the inner or facing edges of the straps and its free end overlying the panel 13. The lateral projections 25 engage the straps 18 adjacent their connections to the panel 13, but ordinarily such engagement is at points spaced somewhat from the panel 13, due to the thickness of the flaps underlying the tongue. The projections 26, if provided, overlie the portion of the panel 15 between the hinge line 24 and the adjacent fold line 22, and are so proportioned as not to interfere with this disposition of the tongue. It will be seen that the distance between the panels 13 and 15, and hence the angular disposition of the straps 18 and the distance they extend from the panels, for any given length of the straps, are determined by the length of the tongue, or more precisely, by the distance from the hinge line 24 to the lateral projections 25.

The panels 13 and 15 ordinarily are disposed in substantially a common plane, except as they may be jogged or deflected relative to each other by reason of the overlapping of the flaps and tongue, as shown, but if desired they may be disposed in angular relation to each other, or may be curved.

A plurality of sheets, such as glass sheets, for example, arranged as a pack in face to face relation with protective paper or the like therebetween if desired, is disposed in the packing element with the sheet edges abutting against the tongues 23 and the marginal portions engaged between the straps 18. In Fig. 2, the packing element 11 is shown as arranged for disposition along a straight edge of a sheet pack, with both parts or sections extending in alignment with each other, while in Fig. 1 the packing element is shown as bent on the hinge line 12 so as to extend about a rectangular corner of the sheets, one section engaging on one of the corner edges and the other section on the other edge. Of course, the sections may be disposed on other than right-angled corners. The packing element 11 may thus be used either as an edge packing or as a corner pad. A number of the packing elements are disposed about the periphery of the sheet pack in accordance with proper packing requirements, and the sheet pack and packing elements enclosed in a case, carton, crate, or the like, designated by C in the drawings, the length and width of which are somewhat greater than the corresponding dimensions of the sheets to allow for the packing elements, and the interior breadth of which corresponds to the width of the packing elements, so that play or movement of the contents in the case C is substantially eliminated. Thus the pack of sheets is cradled by the packing elements, being spaced and cushioned from the case walls parallel to the sheet faces by the straps 18, and from the walls parallel to the sheet edges by the panels 13 and 15, flaps 19, and tongues 23. Shocks or blows to which the case may be subjected are largely, if not entirely, absorbed by the packing elements, and the spacing of the outer sheet faces from the paralleling case walls protects the sheets against a certain amount of deflection of such walls, as under a blow.

Although the packing element 11 is disclosed as applied to a plurality of glass sheets or the like, it will be obvious that it may be used with only a single sheet or flat article, such as a framed picture, the spacing between the straps 18 being determined by the edge thickness of the article or articles. Similarly, more than two straps may be provided to hold separate sheets or groups of sheets in spaced relation to each other. The flaps 19 may be of unequal lengths, and one or both may be omitted if desired. It will be clear that if desired the packing element may consist of only one section instead of two as shown, and as hereinafter explained may comprise more than two sections.

In Figs. 4 to 7 there is illustrated another embodiment of the invention. The blank 30 and packing element 31 of this form are in most respects the same as those of Figs. 1 to 3, differing in the provision of means affording a positive securing lock between the tongue and straps. Those parts of the blank and packing element which are substantially identical to the corresponding parts of the first-disclosed form are designated by the same reference numerals. The blank 30 and packing element 31 formed therefrom comprise panels 13, 14, and 15, a tongue 23

being formed from the panel 15 and straps 18 from the panel 14 as in the first embodiment described. Instead of the pair of flaps 19, however, two flaps 32 and 33 are formed from each panel 14, extending respectively from the panels 13 and 15, by a transverse slit 34 extending from one slit 16 to the other. The transverse slit 34 in the blank is located closer to panel 13 than panel 15, so that the flap 32 is longer than the flap 33. A notch 35 is formed in the inner edge of each of the straps 18 by a suitable cut. The notches 35 are located adjacent the panel 13, but spaced from the connections thereto of the straps by approximately the thickness of the material of the blank. The material separated from the straps to form the notches may be removed, but it is simpler to leave it attached to the flap 33, as shown. On the longitudinal edges of the tongue 23, adjacent the projections 25, lugs 36 are provided extending laterally from the tongue a distance corresponding to the depth of the notches 35.

The packing element 31 is formed by folding the blank 30 in the same manner as the blank 10 to set up the element 11, but when the tongue 23 is disposed between the straps 18, the lugs 36 are engaged in the notches 35. The tongue is thus positively locked in its securing position, and its frictional engagement with the strap edges becomes secondary and need not be relied upon to secure the panels and straps in the desired relation. The longer flap 32 is preferably disposed between the shorter flap 33 and the tongue 23, with substantially its entire extent in surface contact with the tongue, thus providing a firmer cushioning pad. It is for this reason that the notches 35 are spaced from the panel 13. If desired, however, the shorter flap may extend between the tongue and longer flap. In such case, the notches 35 may, but need not, be located adjacent the connections of the straps 18 to the panel 13. The packing element 31 is employed in the same way as the packing element 11, as will be evident from Fig. 7, and may similarly be modified for specific applications or to suit the desires of the maker or user.

A third form of the packing element of this invention is disclosed in Figs. 8 to 10, in which a blank 40 is shown from which a packing element 41 is formed. The blank has a plurality of sections each comprising a panel 42 and a panel 43 connected thereto along a fold line 44. Another panel 42 is connected to the opposite edge of panel 43 along a fold line 45, and so on to the other end of the blank, where a terminal panel 43 instead of a panel 42 is connected to a panel 43, although of course a panel 42 might be employed at such terminal panel. Each panel 43 is cut by parallel slits 47 extending longitudinally of the blank between the fold lines 44 and 45 and by a central transverse slit 48 between the slits 47, to provide straps 49 and flaps 50 similar to the straps and flaps of the previously described forms. Each strap 49 has a central transverse fold line 51 parallel to the fold lines 44 and 45, which define the strap connections to the two panels 42 between which the straps extend. A tongue 52 is formed from each panel 42, having a hinge line 53 at its base parallel to the fold line 44, and longitudinal edges extending from the hinge line 53 in a direction opposite from the fold line 44 to the free end of the tongue, which lies remote from the straps 49. Lateral projections 54 are formed at the free end of the tongue. At its hinge line 53, the tongue 52 is of substantially

the same width as the flaps 50, with the end points of the hinge line substantially in alignment with the slits 47, but the longitudinal tongue edges flare from its base toward its free end so that at least a portion of the tongue adjacent its free end is wider than the flaps 50, or in other words than the space between the straps 49.

The packing element 41 is formed from the blank 40 in substantially the same way that the 10 packing elements 11 and 31 are set up from their blanks, each pair of straps 49 being folded out of the plane of the blank by means of the fold lines 44, 45, and 51, with the panels 42 which they 15 connect disposed closer to each other than in the blank, and the flaps 50 in overlapped relation. Each tongue 52 is swung out from its panel 42 into tight frictional engagement with the inner or facing edges of the bent straps 49, overlying the flaps 50, with the projections 54 engaging the 20 straps adjacent fold line 45. The wedged engagement of the tongue between the straps due to its flared construction secures the straps 49 and panels 42 connected thereby in the desired relation, and the lateral projections 54 are of secondary importance and may even be dispensed with if no longitudinal tension is to be applied to the packing element.

The packing element 41 may include a base member 55 underlying and secured to the panels 42 by any suitable means, as adhesive, and bridging the space therebetween. If of sufficient strength, this base member may be relied upon to hold the panels and straps in the desired relation, and the tongues 52 need not be employed 30 except as providing a thickness of cushioning material additional to the flaps 50. The base member 55 may extend beyond an end, or both ends, of the packing element and be used to secure the packing element encircling a sheet of glass or the like by overlapping the meeting ends of the element, or to secure a plurality of the packing elements in end-to-end relation for obtaining a 35 desired length. In Fig. 9, a packing element 41 is shown applied about an edge of a sheet of glass, and it will be apparent that either a single packing element, or a plurality of packing elements 41 connected by overlapping of the base members 55, may be used to encircle the sheet. If the material is sufficiently flexible, the element 40 is simply bent about the sheet corners, as shown, while if more rigid material is used, the panels 42 may be provided with fold lines like the line 43 of element 11, or the element 41 may be bent on the fold line 44 or 45. For a packing element 50 of relatively light material, such as shown, which is sufficient for the protection of a single sheet of glass or the like, the base member 55 may be a strip of gummed paper tape, which is convenient to handle and apply. It should be clear 55 that the base member may be secured on the packing element, after it is set up from the blank, either before or after the packing element is applied to the article or articles it is to protect. It 60 will also appear from Fig. 9 that the packing element of this invention will conform closely to the sheet edges even when they are curved, particularly when a base member is employed in the manner set forth to bind the packing element tightly against the article edge. Of course, the base member may be of any desired thickness and rigidity, and it may be in sections corresponding 65 to the sections of the packing element proper, either separated or hinged connected.

While the packing element 41 is disclosed as 70 consisting of several sections, it may, like the

packing elements 11 and 31, consist of two sections, or only a single section. Instead of alternating panels 42 and 43, a panel 42, a panel 43, a hinging panel or panels, a second panel 43, and a second panel 42 may be arranged consecutively to provide two connected sections as in the packing element 41, and this arrangement may be repeated as often as desired. The second panel 42 with its tongue may be disposed oppositely to the first panel 42. Again, the packing element 41 may be modified by providing a hinging panel between each panel 42 and one of the panels 43 to which it is connected. Of course, the packing element may readily be formed to accommodate a plurality of sheets or similar articles instead of a single sheet as shown. The packing element 41 may also be varied from the specific form shown by using the lug and notch lock of the packing element 31 instead of the flared tongue 52.

On the other hand, the packing elements 11 and 31 may be formed to provide more than two sections, like the packing element 41, by having the lateral projections 25 and 26 of the tongues 23 terminate short of the side edges of the panels 15 from which they are cut, to leave portions of panels 15 which may connect with adjacent panels, substantially as in the case of the panels 42 and tongues 52. Each of the packing elements 11 and 31 may also comprise the packing element proper and a base member, as in the case of the element 41. Similarly, the flared tongue construction of the packing element may be employed in the elements 11 and 31 instead of the tongue structures specifically disclosed in connection with those packing elements.

All of the forms of the packing element may be varied in many ways, as by the provision of more than one fold line along the length of the straps, or by the omission of fold lines in the straps where the material is sufficiently flexible, so that the straps may be bent otherwise than in the specific angular relation shown. Instead of a pair of flaps each extending from one of the panels connected by the straps, a single flap extending from one of the panels may be used, which may be folded on itself to provide a desired cushioning thickness. If desired, the free end of the tongue may be secured to the panel it overlies, or the tongue may be secured to an underlying flap or flaps, or the flaps may be secured together.

It is to be understood that my invention contemplates the modification of the several disclosed embodiments not only in the ways suggested hereinabove, but to provide changes and variations which will readily suggest themselves without requiring departure from the scope of the inventive concept. It is therefore not intended that the invention be limited otherwise than as required by the appended claims, with due regard to the spirit as well as the literal wording thereof.

I claim:

1. A packing element comprising a substantially oblong strip of paperboard cut and scored to provide a pair of panels spaced apart lengthwise of said strip, a pair of straps at the sides of and of materially less width than said strip and extending lengthwise thereof and severed therefrom at their inner edges, said straps being spaced apart transversely of said strip and respectively attached at their ends to the inner edges of said panels along fold lines extending transversely of said strip, said straps being folded

upward providing substantially inverted V-shaped elements spaced apart transversely of said strip and having downwardly diverging arms, and a tongue member separate from said arms cut from said strip and attached at one end thereto along a transverse fold line, said tongue member having a length materially greater than twice the thickness of said strip of paperboard and being folded over between said V-shaped elements, the arms of said V-shaped elements and said tongue having cooperating means effective for restraining said arms against movement away from each other.

2. A packing element comprising a substantially oblong strip of corrugated paperboard cut and scored to provide a pair of straps extending lengthwise of said strip at opposite sides thereof, said straps being spaced apart transversely of said strip and severed therefrom at their inner edges and attached at their ends to said strip along transverse fold lines, said straps being folded upward providing substantially inverted V-shaped elements spaced apart transversely of said strip and having downwardly diverging arms, two superposed elements integral with said strip underlying the area between said V-shaped elements and providing two thicknesses of the corrugated paperboard of said strip, and a tongue member separate from said arms cut from said strip and attached at one end thereto along a transverse fold line, said tongue member having a length materially greater than twice the thickness of said strip and being folded over between said V-shaped elements, the arms of said V-shaped elements and said tongue having cooperating means effective for restraining said arms against movement away from each other, said tongue seating on the upper face of the upper one of said two superposed elements providing with the latter a cushion comprising three thicknesses of the paperboard of said strip.

3. A packing element comprising a substantially oblong strip of corrugated paperboard cut and scored to provide a pair of straps extending lengthwise of said strip at opposite sides thereof, said straps being spaced apart transversely of said strip and severed therefrom at their inner edges and attached at their ends to said strip along transverse fold lines, said straps being folded upward providing substantially inverted V-shaped elements spaced apart transversely of said strip and having downwardly diverging arms, two superposed elements integral with said strip underlying the area between said V-shaped elements and providing two thicknesses of the corrugated paperboard of said strip, and a tongue member separate from said arms cut from said strip and attached at one end thereto along a transverse fold line, said tongue member having a length materially greater than twice the thickness of said strip and being folded over between said V-shaped elements and provided at its free end with abutments engaging the adjacent arms of said V-shaped elements effective for restraining the arms of said V-shaped elements against movement away from each other, said tongue seating on the upper face of the upper one of said two superposed elements providing with the latter a cushion comprising three thicknesses of the paperboard of the strip.

4. A packing element comprising a substantially oblong strip of corrugated paperboard cut and scored to provide two panels spaced apart lengthwise of said strip, a pair of straps extending between said panels at opposite sides of said

strip severed therefrom at their inner edges and respectively attached to the inner edges of said panels along transverse fold lines, said straps being spaced apart transversely of said strip and folded upward providing substantially inverted V-shaped elements spaced apart transversely of said strip and having downwardly diverging arms, a first flap integral with one of said panels extending therefrom substantially in the plane thereof and underlying the area between said V-shaped elements, a second flap integral with the other of said panels extending therefrom in underlying relation to the area between said V-shaped elements and seating on the upper face of said first flap, and a tongue member separate from said arms attached at one end to one of said panels along a transverse fold line, said tongue member having a length materially greater than twice the thickness of said strip and being folded over between said V-shaped elements, the arms

10 of said V-shaped elements and said tongue having cooperating means effective for restraining said arms against movement away from each other, said tongue seating on the upper face of

15 said second flap providing therewith and with said first flap a cushion comprising three thicknesses of the paperboard of said strip.
